UNITED STATES PATENT OFFICE.

GEORGE K. THOMPSON, OF SUMMIT, NEW JERSEY.

STORAGE BATTERY.

Application filed August 31, 1923. Serial No. 660,268.

This invention relates to improvements in storage batteries, the main object being to provide a strong and simple substitute for the series of rubber cells and the protective wooden box ordinarily used to enclose the cells. Instead of using these several elements, the device hereafter described comprises a single casting, preferably made of lead or an alloy, or other suitable substance that can be molded to produce the plurality of cells, the container made in this manner being strong enough to withstand the service shocks in an automobile, without being enclosed in another receptacle. In addition to utilizing a single body of metal for the several containers of a storage battery, the invention preferably comprises handles formed integral with the single body of metal, and ribs whereby the metal is reinforced below the handles.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended.

Fig. I is a longitudinal section of a storage battery container embodying the features of this invention.

Fig. II is a transverse section of the container.

The container comprises a bottom wall 1, side walls 2, end walls 3 and partitions 4 parallel with the end walls, all of these parts being integrally connected together. A plurality of cells are thus formed by a single body of metal.

Ribs 5 extend upwardly from the bottom of the cells to support the positive and negative plates in the usual manner. These ribs are parallel with the side walls, and they are preferably integral with the container.

Handles 6 lie above the end walls, each handle having downwardly extending portions 7 at its ends integrally connected at the upper edge of the end wall. Each end wall is provided with a horizontal reinforcing rib 8 at its upper margin and reinforcing ribs 9 converging downwardly from the ends of said horizontal rib, all of said ribs being on the outer face of the end wall at

points directly below the handle, and the three ribs may be in the form of a triangle extending from the top to the bottom of the end wall. The handles are thus very effectively reinforced by ribs formed integral with the end walls.

All of the elements previously described are preferably made of metal, and the several parts are formed by a single casting, providing a strong, simple, durable and most effective substitute for the numerous separate elements which are ordinarily assembled to produce the containers and handles of a storage battery.

To economize in the manufacture and at the same time obtain the desired strength, the container is preferably made of an alloy comprising lead, antimony and other impurities, although the invention is not limited to the use of these elements.

Since the container is preferably made of metal having the necessary strength to withstand the service shocks without the protection of an outer container, and this metal being a conductor of electricity, the inner faces of the container are coated with an insulating acid-resisting substance as shown at 10.

As a further safeguard, to prevent the transmission of electrical energy through the walls of the metal container, the outer faces of said container are likewise coated with an insulating acid-resisting substance 10'. The substance 10-10' may be a rubber composition or an asphaltic composition adapted to withstand the action of the acid in the battery, and also adapted to serve as an insulator to prevent the transmission of an electric current through the walls of the container. This substance, while in a liquid state, can be conveniently applied by dipping the container into the same.

I claim:

1. A storage battery container made of metal and having a partition formed integral therewith to provide a plurality of cells within said container, an insulating acid-resisting substance applied to the entire interior surface of said container, including said partition, as a liner therefor, handles located at opposite ends of the container and formed integrally with the walls thereof, and reinforcing ribs extending heightwise and widthwise of the walls to distribute throughout the entire area of the wall tension that is imparted thereto in lifting the container by means of said handles.

2. A storage battery container made of metal and having a partition formed integral therewith to provide a plurality of cells within said container, handles extending 5 from oppositely disposed walls of said container and integral therewith, reinforcing ribs formed integrally with said oppositely disposed walls to distribute throughout the area thereof tension that is imparted to the 10 walls in lifting the container by means of the handles, said reinforcing ribs upon each of the oppositely disposed walls being ar-

ranged in the form of a triangle having one of its sides located adjacent to the handle formed integrally with the wall and an apex of the triangle located at the bottom of said wall substantially midway of the width thereof, and an insulating acid-resisting substance applied to the interior surface of said container, including said partition, as 20 a liner therefor.

In testimony that I claim the foregoing I hereunto affix my signature.

GEORGE K. THOMPSON.
